CLOTHES STICK

William F. Heuer, Quincy, Ill.

Application September 16, 1939, Serial No. 295,313

1 Claim. (Cl. 294—23.5)

The present invention relates to clothes sticks, and the primary object of the invention is to provide a novel and improved clothes stick for manipulating clothes or other articles in a washing machine, and more particularly for separating and lifting clothes or articles from a washing machine after the washing thereof has been completed, so that they may be passed through a wringer or otherwise further treated, as may be desired.

The improved clothes stick, according to the present invention, is provided on its operative end with a head of novel formation whereby puncturing, tearing or other injury to the clothes or similar articles is avoided, and is provided adjacent to the head with an annular claw-like edge which is capable of securing a grip upon the wet clothes or other fabric articles when pressed down and drawn laterally thereover, thus enabling the water soaked clothes or similar articles to be readily separated and lifted and removed from the body of washing solution in the washing machine preparatory to the passing thereof through a wringer or other further treatment, without danger of tearing or otherwise injuring the clothes or other articles.

A further object of the invention is to provide a clothes stick of this character having circumferential grooves in the handle portion thereof to prevent slipping of the wet stick in the hand of the operator.

In the accompanying drawing:

Fig. 1 is a side view of a clothes stick embodying the present invention;

Fig. 2 is a longitudinal section of the operative end of the stick, taken on the line 2—2 in Fig. 1;

Fig. 3 is a cross section of the stick taken on the line 3—3 in Fig. 1;

Figs. 4 and 5 are diagrammatic views showing the manner in which the stick operates in the separation and lifting of the wet clothes or other similar articles; and

Fig. 6 is a side view of another form of the clothes stick embodying the present invention.

The improved clothes stick designated 1 in Fig. 1, is turned preferably from a piece of hard or semi-hard wood of suitable length to form a handle portion 2 at one end, and a substantially hemispherical head 3 at the other end, this head being concentric with the axis of the stick, and the stick is turned to a substantially reduced diameter to form a neck portion 4 behind or adjacent to the head. According to the present invention, an annular concave shoulder 5 is undercut into the head where it joins the neck por-

tion 4. This shoulder has a surface of revolution about the axis of the stick tangents C and D, the peripheral portions of which converge to a point O which is offset from the diameter A—B and toward the body of the head, these tangents C and D being at an acute angle to the peripheral surface of the head, thus forming an annular sharp or claw-like edge 6 which surrounds the hemispherical head where it joins the shoulder. In order to prevent slipping of the stick in the hand of the operator, the handle portion 2 is provided with a suitable number of circumferential grooves 7 which enable the hand of the operator to obtain a firm grip upon the stick and prevent slipping thereof, even though wet.

In the form of the invention shown in Fig. 6, the stick is constructed similarly as described above with reference to Figs. 1 to 3 inclusive with the exception however that the handle portion 2^a is turned intermediately of the length of the stick and provided with the circumferential anti-slip grooves 7^a, and the stick is tapered toward both ends to form the necks 4^a of relatively reduced diameter, and the extremities of these necks are provided with hemispherical heads 3^a which provide the annular acute or claw-like edges like those shown and described with respect to Figs. 1 to 3, so that the form of stick shown in Fig. 6 is duplex or both of its ends are operable to separate and lift the clothes or other articles. In the single type of stick shown in Fig. 1, the handle end thereof may be provided with a groove 8 in which may be secured a cord or the like 9 by which the stick may be hung upon a nail or other support and thereby avoid breakage or other injury to the relatively sharp or claw-like edge 6.

In using a clothes stick according to either form of the invention shown, the stick is grasped by its handle portion by the operator and an operative end of the stick having the hemispherical head thereon, is plunged down into the water and onto the piece of clothing or other article X to be separated or removed and then swung laterally. The plunging of the head of the stick into the water creates a suction behind the head, causing water to flow around the head toward the smaller-diameter neck portion of the stick, thereby causing a portion of the wet piece of clothing or other article floating or submerged in the water in the washing machine to be carried over the shoulder and to lap sharply or acutely over the claw-like edge 6 of the head, substantially as shown in Figs. 4 and 5, thus enabling the stick to pick up the clothes easily, and this

sharp edge of the head will obtain a firm grip on the wet and slippery piece of clothing or other article in a manner comparable with that in which the finger nail of the hand of the operator has heretofore been employed. As the stick is lifted, the grip of the annular relatively sharp or claw-like edge 6 on the head of the stick will secure the piece of clothing or other article thereto with sufficient firmness to prevent slipping of the wet and relatively heavy piece of clothing or other article therefrom and to avoid tearing, puncturing or other injury thereto under the weight thereof, thus enabling the piece of clothing or other article to be separated and lifted with facility from the water or liquid in a washing machine in which the pieces of clothing are otherwise relatively inaccessible, and to be caught by the operator and entered into the wringer or otherwise disposed of for further treatment. Clothes sticks embodying the present invention thus enable pieces of clothing or similar articles to be easily and quickly separated and removed from the hot water in a washing machine without the necessity of the placing of the hands of the operator into the water, and puncturing, tearing or other injury to the pieces of clothing or other fabric articles is avoided by the rounded shape of the hemispherical head and by the extended length of the continuously annular form of the sharp or claw-like edge adjacent to or behind the head which secures the grip upon the piece of wet clothing or other article.

Obviously, clothes sticks embodying the present invention may be made of materials of different kinds. It is preferable however to turn them from wood in order that they may be made inexpensively, and hard or semi-hard wood is preferable in order to minimize denting or breaking of the annular relatively sharp or claw-like edge on the head.

I claim as my invention:

A clothes stick formed from a single piece of 10 wood and having an elongated cylindrical portion at one end constituting a handle, a substantially hemispherical portion at its other end constituting a head, and an intermediate portion tapering gradually and continuously without interruption from the handle portion to said head, the reduced end of said tapered intermediate portion connecting into the rear of said head at substantially the center thereof and having a smaller area than the rear of said head whereby 20 the marginal rear face of the head provides an annular shoulder, the rear face of the head providing said shoulder being grooved circumferentially with the base of said groove disposed at substantially an acute angle to the adjacent peripheral surface of the head so that the junction between the rear face of said head providing said shoulder and the peripheral surface of said head is relatively sharp and provides a circular edge for 25 clawing engagement with the clothes. 30
